UNITED STATES PATENT OFFICE

106,060

DESIGN FOR AN ARTIFICIAL FISH BAIT

Carl S. Raymond, Flint, Mich.

Application January 22, 1937, Serial No. 67,240

Term of patent 14 years

To all whom it may concern:

Be it known that I, Carl S. Raymond, a citizen of the United States, residing at Flint, Genesee county, State of Michigan, have invented a new, original, and ornamental Design for an Artificial Fish Bait, of which the following is a specification, reference being had to the accompanying drawing forming part thereof.

Fig. 1 is a plan view of an artificial fish bait showing my new design.

Fig. 2 is a side elevation.

I claim:

The ornamental design for an artificial fish bait, as shown.

CARL S. RAYMOND.
